[57] CLAIM

The ornamental design for a pool cleaner debris bag, as shown and described.

DESCRIPTION

FIG. 1 is a bottom perspective view of a pool cleaner debris bag showing our new design;

FIG. 2 is a bottom plan view thereof;

FIG. 3 is a top plan view thereof;

FIG. 4 is a side elevation view thereof;

FIG. 5 is a rear elevation view thereof;

FIG. 6 is a side elevation view of the opposite side of FIG. 4; and,

FIG. 7 is a front elevation view thereof.

The crosshatch shading shown in all views is understood to repeat throughout the indicated areas.
